United States Patent Office

Des. 179,222
Patented Nov. 13, 1956

179,222

LOCOMOTIVE BODY OR THE LIKE

Carl F. Schaus, Hagaman, N. Y., and John K. Erzer,
Erie, Pa., assignors to General Electric Company, a
corporation of New York

Application February 10, 1955, Serial No. 34,448

Term of patent 14 years

(Cl. D66—1)

Fig. 1

Fig. 2.

Fig. 3.

Fig. 4.

Fig. 4 is a front elevational view thereof.

Fig. 1 is a side elevational view of a locomotive body or the like, showing our new design with the side opposite being substantially the same as the one shown;

Fig. 2 is a top plan view;

Fig. 3 is an enlarged fragmentary perspective view; and

The characteristic feature of our design resides in the configuration of the portion forward of the windshield.

We claim:

The ornamental design for a locomotive body or the like, substantially as shown and described.
